UNITED STATES PATENT OFFICE

PERCY B. CAMP, OF MAYWOOD, ILLINOIS, ASSIGNOR TO UNIVERSAL DRAFT GEAR ATTACHMENT CO., A CORPORATION OF ILLINOIS

RAILWAY BRAKE

Application filed February 20, 1930. Serial No. 430,081.

This invention relates to railway brakes and more particularly to the means for securing the ends of the brake operating cable to the anchoring device.

5 The principal object of the invention is the provision of new and improved means for securing the ends of a brake operating cable to its anchoring device.

10 Another object of the invention is the provision of a new and improved anchoring device for cables and the like that is provided with means for locking the parts together in such a manner that any force exerted on the cable tends to more securely lock the anchor 15 device to the cable.

A further object of the invention is the provision of new and improved means for securing the ends of a cable to their respective anchoring devices that is inexpensive to 20 manufacture and assemble and that is simple in construction and efficient in use.

25 Other and further objects and advantages of the invention will appear from the following description taken in connection with the accompanying drawing, in which

Fig. 1 is a side elevation of a portion of a railway brake with parts broken away and showing an anchor device for one end of the brake operating cable in position thereon;

30 Fig. 2 is a side elevation of a portion of a brake operating mechanism showing an anchor member for the opposite end of the brake operating cable;

Fig. 3 is a vertical section of the anchor member shown in Fig. 1, showing the parts in assembled relation;

Fig. 4 is a similar view but showing the parts in partially disassembled relation;

Fig. 5 is a section on line 5—5 of Fig. 3;

40 Fig. 6 is an elevation of the anchor device with the cable removed;

Fig. 7 is an elevation of a modified form of construction;

Fig. 8 is a vertical section thereof;

45 Fig. 9 is a vertical section on line 9—9 of Fig. 2, showing the parts in assembled relation and with parts broken away; and

Fig. 10 is a vertical section of the anchor device shown in Fig. 9 with the parts in partially assembled relation.

Referring now to the drawing, the reference character 10 designates a railway brake operating mechanism comprising a casing 11 in which a drum 12 for winding up the brake operating cable 13 is journaled. The drum 55 12 is rotated by means of the hand wheel 14 operating through the pinion 15 and gear 16 as is usual in such constructions. The brake operated cable 13 is anchored to the gear 16 as at 17 and extends downwardly and about a pulley 18 at the lower portion of the car in the usual manner.

The means for anchoring the upper end of the cable 13 to the gear 16 comprises a plate 19 rigidly connected at one end to the gear 60 65 and having its opposite end spaced therefrom and provided with an opening through which a bolt or shaft 21 extends and on which the anchor member 22 is movably mounted.

It is common practice to provide the end 70 of the cable with an enlargement which usually is tapered and is adapted to engage a corresponding tapered opening in the anchor member for connecting the end of the cable thereto. Considerable difficulty is experienced in preparing this enlarged end because the metal forming the same must be firmly attached to each individual wire of each strand otherwise the enlargement will be pulled loose from the rope by the repeated 75 force applied to the cable in setting the brakes.

In forming this enlargement, it is the present practice to tie a band around the end of the wire cable to limit its untwisting, untwist 80 the end of the cable, remove the hemp core, and then brush out the cable end, that is, untwist the strands so that the individual wires will be separated. The cable end has now 85 the appearance of a brush.

The brush portion is then treated with a cleaning fluid such as a weak acid, and then tinned, after which the wires of the brushed end are brought together and a tie wire passed 90 around the same, preparatory to threading the end through the axial opening in the socket or anchor member. After the tinned end 95 has been threaded through the axial opening in the socket the tie is removed and the wires again expanded in the socket or conical open- 100

ing, after which the molten metal for forming the anchor plug is poured into the socket occupied by the wire ends of the cable. This arrangement is objectionable because of the time and labor involved in forming the enlargement.

The present invention seeks to eliminate the necessity for so firmly attaching the enlargement to the end of the cable by providing means that will clamp the end of the cable when a pulling force is applied thereto. The enlargement is applied simply by removing the core, threading the coreless end through the opening in the socket or anchor member, placing the wedge in position, end then pouring the molten metal in the socket over the end of the cable. This process will occupy about one-twelfth to one-fifteenth of the time required by the old method of untwisting, cleaning and tinning the individual wires.

In Figs. 1 and 3 is shown one form of anchor member which is by way of example only. In this form of construction the anchor member 22 comprises a head portion 23 and a shank or sleeve portion 24.

The head portion 23 comprises a pair of side plates 25 and 26, see Fig. 6, spaced apart and connected together at their central portion by a hub or anchor bar 27. These side plates and the hub may be cast integral as shown in Fig. 6. The anchor member or hub 27 is provided with a circumferential groove for receiving the bight or loop 20 of the cable 13 as clearly shown in Figs. 3 and 4 of the drawing.

The anchor bar or hub 27 is provided with an axial opening 28 through which the pin or bar 21 is adapted to extend for connecting the anchor member to the gear 16.

The shank member 24 is provided with an opening 29 extending downward from the hub 27. This member is preferably elliptical in cross-section as shown in Fig. 5 and the major axis of this elliptical opening is sufficient to permit the two side portions of the loop or bight to be spread apart far enough for receiving a wedge 31 as will presently appear.

One end wall of the opening 29 may be provided with an inclined wedging surface 32 as at 32 for engaging a corresponding inclined surface on the tapered or conical enlargement 33 secured to the end of said cable. The wedge member 31 is also provided with an inclined wedging face 34 for engaging the corresponding inclined surface of the enlargement 33 as clearly shown in Fig. 3 of the drawing. When the wedge is in position the inclined surfaces 32 and 34 cooperate with the sides of the sleeve 24 to form a conical socket into which the molten metal for forming the enlargement 23 is poured as will presently appear.

In assembling the device the hemp core 30 is removed, the end of the cable is inserted through the opening 29 and around the hub

27 and back through the opening 29, as shown in Fig. 4, the wedge 31 is placed in position and the molten metal is poured into and around the end of the cable in the socket formed by the inclined surfaces 32 and 34 and the sides of the sleeve 24. The inner end of the wedging member 31 will come in contact with the hub 27 and any further force applied to the cable 13 will cause the wedging member 31 to be forced by the conical enlargement 33 into frictional engagement with the cable 13 as clearly shown in Fig. 3 of the drawing. The bight or loop in the cable, together with the frictional contact between the wedge 31, cable 13 and the wall of the opening 29 will firmly grip the end of the cable and securely anchor the same to said anchor member.

If desired, the hub 27 may be provided with a flat face 35 in alignment with the opening 29 whereby a sharp turn will be given to the cable at the point where it turns around said hub, thereby more firmly anchoring the cable to the anchor device.

Since only a small amount of the force exerted on the cable after the same has been assembled as shown in Fig. 3 will be transmitted to the enlargement 33 this enlargement may be readily and easily applied, thereby effecting a tremendous economy in time and labor.

In the modified form of construction shown in Figs. 7 and 8 the anchor device 36 comprises a head 37 and a shank 38. The head 37 comprises an offset plate 39 having an opening 41 therethrough, the opening 41 being adapted to receive the pin or shaft 21 for attaching the device to the gear 16. The shank portion 38 is provided with an opening 42 having the converging or wedging walls 43 and 44 at each end thereof for engaging the sides of the loop 45 of the brake operating cable 13a. Instead of extending the loop 45 of the cable about a fixed shaft or hub as in the previous construction it is extended about a wedge-shaped movable anchor member 46. Both the opening 42 and the anchor member 46 converge outwardly whereby when the parts are assembled and force is applied to the cable 13a both sides of the loop 45 will be forced into frictional engagement with the inclined side walls 43 and 44 for firmly securing the cable to the anchoring device.

The end of the cable 13a may be provided with an enlarged portion or band as shown at 47 for preventing the untwisting of the strands of the cable.

In Figs. 2, 9 and 10 is disclosed a construction for attaching the lower end of the brake operating cable to the brake operating rod 48. A holding member 49 is attached to the outer end of the rod 48 in any suitable manner as by being threaded into said member as shown in Fig. 9. The holding member 49

is in the form of a casing having an enlarged opening 51 in one side wall thereof through which the anchor member 52 may be inserted as will presently appear.

5 A slot 53 extends from the enlarged opening 51 partially across the end wall 54 through which the cable 13a is adapted to extend. The end of the cable 13a is provided with an anchor member 52 which is in the 10 form of a head 55 which is adapted to engage the recess within the casing 49. This head is provided with an opening 56 for receiving a loop 57 of the cable 13a as shown in Fig. 9.

One or both end walls of the opening 56 15 may be inclined to form a wedging surface. As shown, the end wall 58 is provided with the inclined surface 59 for this purpose. A wedging member 61 is provided for engaging within the loop 57 of the cable. This wedge 20 is preferably though not necessarily provided with a peripheral groove 62 for receiving the two sides of the loop. The opening 56 and the wedge member 61 converge outwardly so that when the parts are in assembled relation any force applied to the cable 25 will tend to wedge the sides of the loop against the end walls of the opening 56 for anchoring said cable.

In assembling the device, the cable 13a is 30 passed through the opening 56 and is returned through said opening to form the loop 57. The wedge 61 is inserted in the loop and force is applied to the cable to force the wedge into said opening for binding the 35 two sides of the loop of the cable against the walls of said opening for anchoring the cable to said device. After the cable has been anchored to the anchor member 52, said member is inserted in the casing through the opening 40 51, the cable 13a passing into position through the slot 53.

In all forms of construction the parts are so arranged that the body portion of the cable will be at an angle to the adjacent portion 45 of the loop, whereby the frictional resistance of the loop against the cooperating friction surface will be increased.

I claim as my invention:

1. In combination, an anchor device 50 provided with an opening extending longitudinally thereof, one of the walls of said opening being inclined, a brake operating cable having one of its ends looped and extending into said opening, a wedge member in said 55 loop for wedging one side portion of said loop against said inclined wall, and a holder member for engaging said anchor device, said holder member being provided with means for connecting the same to a brake operating 60 device.

2. In combination, an anchor device 65 provided with an opening extending longitudinally thereof, one of the walls of said opening being inclined, a brake operating cable having one of its ends looped and extending

into said opening, a wedge member in said loop for wedging one side portion of said loop against said inclined wall, and a holding member comprising a casing, one side wall of said casing being provided adjacent 70 one end with an enlarged opening and with a slot extending from said opening partially across one end of said casing whereby said anchor may be inserted into said casing through said opening with said cable engaging 75 said slot.

3. In combination, a holding element comprising a casing member, one side wall of said casing member being provided adjacent one end with an enlarged opening and with 80 a slot extending from said opening partially across the opposite end of said casing member, an anchor member insertible through said opening into said casing member and slidably therein, said member having an 85 opening therethrough parallel with said slot, one of the defining walls of said opening being inclined to the longitudinal axis of said casing member, a cable extending through said last named opening and means engaging 90 said cable and inclined wall for anchoring said cable to said member, said cable extending through said slot.

In testimony whereof I affix my signature.
